*Primary Examiner—Louis S. Zarfas
Attorney, Agent, or Firm—Jerry Semer*[57] **CLAIM**

The ornamental design for a liquid filled shoe insole, as shown and described.

DESCRIPTION

FIG. 1 is a top plan view of a liquid filled shoe insole showing my new design with a triangular design in toe portion in dotted lines;

FIG. 2 is a side elevational view;

FIG. 3 is a sectional view taken on line 3—3 of FIG. 1;

FIG. 4 is a bottom plan view with the triangular design

in toe portion in dotted lines;

FIG. 5 is a front elevational view; and,

FIG. 6 is a rear elevational view.

The part in dotted lines is not part of the design sought to be patented.
